UNITED STATES PATENT OFFICE.

THOMAS E. HALL, OF OTTUMWA, IOWA.

SPARK-PLUG.

1,362,300.

Specification of Letters Patent. Patented Dec. 14, 1920.

Application filed October 11, 1919. Serial No. 330,040.

To all whom it may concern:

Be it known that I, THOMAS E. HALL, a citizen of the United States, residing at Ottumwa, in the county of Wapello and 5 State of Iowa, have invented certain new and useful Improvements in Spark-Plugs, of which the following is a specification.

This invention relates to improvements in spark plugs especially adapted for use 10 on internal combustion engines.

An important object of this invention is to provide a spark plug having novel means for intensifying the spark at the sparking point of the plug whereby the accumulation 15 of carbon is reduced in the cylinders of the motor and the fuel consumption also reduced.

A further object is to provide a spark plug having a sectional insulator adapted 20 to withstand a maximum of strain due to vibration, etc., whereby breakage of the plug is reduced to a minimum.

A further object is to provide a spark plug having an insulator formed of a pair 25 of sections and novel means to space the sections whereby the several parts of the spark plug are rendered free to expand under the influence of heat without causing a leakage in the plug.

30 A further object of the invention is to provide a spark plug of the character described which is efficient, of highly simplified construction, and cheap to manufacture.

Other objects and advantages of the invention will be apparent during the course 35 of the following description.

In the accompanying drawing forming a part of this application and in which like numerals are employed to designate like 40 parts throughout the same,

Figure 1 is a vertical section through a spark plug embodying the invention.

Fig. 2 is a vertical section through a modified form of insulator.

45 Fig. 3 is a perspective of a spacing element embodied in the invention.

Fig. 4 is a plan view of the lower insulator section illustrated in Fig. 2.

In the drawing wherein for the purpose 50 of illustration is shown several preferred embodiments of the invention, the numeral 5 designates the shell of a spark plug having the usual exterior screw threads 6 adapted to engage the screw threads of the 55 spark plug opening in an internal combus-

tion engine cylinder. An annular shoulder 7 is formed on the shell 5 and is adapted for forcing a gasket into gas-tight engagement with the upper side of the cylinder to which the spark plug is applied as is customary in spark plugs of standard construction. The upper portion of the shell 5 is provided with polygonal sides 8 adapted to be engaged by a wrench for applying the plug.

The invention includes upper and lower insulator sections 9 and 10 respectively, which are retained in spaced relation by a spacing element 11 of insulating material.

Gaskets 12 and 13 surround the sections 70 of the insulator and engage annular shoulders 14 and 15 formed on the same. The gasket 13 which is adapted to coöperate with the gasket 12 for preventing the leakage of compression through the plug is 75 mounted on an annular shoulder 16 formed in the interior of the shell. A locking nut 17 is adapted to secure the sections 9 and 10 of the insulator in position and is also adapted to force the gaskets into gas tight 80 engagement with the inner wall of the shell. As illustrated in Fig. 1 the sides of the annular shoulder 14 and 15 in contact with the gaskets are inclined by forcing the gaskets tightly into engagement with the inner side 85 wall of the shell.

A conductor 18 is extended centrally through the upper insulator section 9 and has its upper end portion screw threaded for engagement with a binding post 19 90 which is adapted for connection with one terminal of a feed wire.

The lower end portion of the upper conductor 18 extends beyond the insulator 9 and is pointed as indicated at 20. The 95 pointed extension 20 of the lower end of the conductor 18 is received within a centrally arranged opening 21 in the annular spacing element 11 and is arranged upwardly from the upper terminal of a second conductor 22. As illustrated in Fig. 1, the conductor 22 is in the form of a wire cable constructed of a plurality of twisted strands of fine copper wire. The upper end portion of the cable 22 terminates flush with the upper end of the lower insulator 10 for forming a spark gap between the pointed extension 20 and the upper conductor 18. The spark gap thus formed between the adjacent ends of the conductors causes the cur- 100 105 110

rent to jump the same in order to reach the firing point of the plug. The spark gap thus formed intensifies the spark at the 5 sparking points and thereby causes the spark to completely ignite the charge of gas within the cylinder. The lower end portion of the cable 22 terminates flush with the lower end of the insulator 10 and is arranged in spaced relation to a pair of 10 stationary electrodes 23. The stationary electrodes are curved downwardly and upwardly toward the end of the cable 22 whereby an efficient spark point is provided between the cable 22 and the electrodes.

15 In the form of the invention illustrated in Figs. 2 and 4, the upper insulator 24 is provided with a centrally arranged conductor 25 having its lower end portion extended beyond the adjacent end of the insulator 20 and split to provide four sparking points 26. The lower insulator 27 is provided with a plurality of spaced parallel conductors 28 arranged in spaced relation to the split sections 26 of the upper conductor 25. The 25 upper and lower ends of the conductors 28 which are of copper wire terminate flush with the upper and lower ends of the insulators for preventing the bending of the end portions of the same as a result of their 30 lightness. In assembling the form of the invention illustrated in Figs. 2 and 4, the insulator 27 is first arranged within the shell and the spacing element is subsequently placed upon the same. The upper insulator 35 24 is now mounted upon the spacing element 11 and the split sections 26 of the conductor 25 are thereby arranged in spaced relation to the upper ends of the conductors 28.

40 As illustrated in Fig. 3, the spacing element 11 is formed of a plurality of built up annular layers of mica some of which may be removed for spacing the ends of the conductors the desired distance.

45 The spacing element 11 permits of the expansion of the several elements of the plug upon being heated without the possibility of leakage or compression. Further in forming the insulator in two sections, the same 50 are less liable to break as the result of ex-

cessive heat and are also enabled to withstand strain and vibration during use.

It is to be understood that the form of the invention herewith shown and described is to be taken as a preferred embodiment of 55 the same and that such minor changes in arrangement and the construction of parts may be made as will remain within the spirit of the invention and the scope of what is claimed.

60

Having thus described the invention, what is claimed as new is:

1. A spark plug including a shell, upper and lower insulators arranged within the shell, a conductor carried by said upper insulator and having its lower end portion extended beyond the lower end of the upper insulator and being split for forming a plurality of outwardly diverging sparking points, a plurality of spaced conductors carried by said lower insulator and having their upper ends terminating flush with the upper end of the lower insulator and arranged in spaced relation to said sparking points, a spacing element arranged between 75 said upper and lower insulators and having a centrally arranged opening receiving the sparking points of said first named conductor, and an electrode carried by the lower end of said shell. 80

2. A spark plug comprising a shell, upper and lower insulators arranged within said shell, a conductor extending centrally through said upper insulator and having its lower end portion extended beyond the 85 lower end of the upper insulator and formed with a plurality of outwardly diverging sparking points, a plurality of spaced parallel conductors extending through said lower insulator and arranged in rectangular 90 formation, the upper ends of said spaced parallel conductors being flush with the upper end of the lower insulator and arranged directly beneath the outwardly diverging 95 sparking points of said first named conductor, an electrode carried by said shell, and means spacing the upper and lower insulator sections.

In testimony whereof I affix my signature.

THOMAS E. HALL. [L. S.]
